UNITED STATES PATENT OFFICE.

VINTON E. SISSON, OF CHICAGO, ILLINOIS, ASSIGNOR TO WALTER P. MURPHY, OF NEW YORK, N. Y.

DROP-END GONDOLA CAR.

1,407,824.

Specification of Letters Patent. Patented Feb. 28, 1922.

Application filed July 6, 1920. Serial No. 394,049.

To all whom it may concern:

Be it known that I, VINTON E. SISSON, a citizen of the United States, residing at Chicago, in the county of Cook and State of Illinois, have invented certain new and useful Improvements in Drop-End Gondola Cars, of which the following is a specification:

My invention relates to drop end gondola cars, and more particularly to an improved hinged construction for hinging the end gate.

Railroad cars known as drop end gondola cars are provided with their drop ends so as to permit the carrying of structures longer than the car, such, for example, as structural steel, telephone poles, and such articles as are usually transported on flat cars. When cars of this type are used for transporting such articles, the end gates are folded down so as to lie flat on the floor; and for this reason the end gates are hinged to the underframe or end sill. When the car is used as a gondola, that is with the end gate raised, there is an outward and upward thrust on the gate due to the pressure of the contents, especially when consisting of bulk material such as sand and coal. If the pressure of the cargo against the end is considerable, as it is likely to be, there is a tendency for the gate to bulge. This is undesirable in itself, as the structure of the gate is weakened and is likely to be given a permanent set which makes it difficult to manipulate. Moreover, any considerable outward bulge tends to draw up the lower edge of the gate at the middle over the floor abutment against which the lower edge of the gate usually rests, causing a gap through which bulk material can leak.

The primary object of my invention is the provision of a hinged construction for end gates which will effectively resist not only the outward thrust on the gate which tends to cause the gate to bulge, but also the upward thrust resulting from the tendency of the lower edge of the gate to draw upward due to bulging. My invention contemplates an arrangement of hinges for the end gates, so constructed and disposed that they act as tension members to hold down the lower edge of the gate, thereby checking its tendency to bulge and preventing possible leakage.

My invention consists in the novel arrangements, constructions and combination

of parts, to be hereinafter claimed, for carrying out the above stated objects and such other incidental objects as will appear from the following description of the preferred embodiment of my invention, shown in the drawings annexed hereto.

In the drawings, in which like characters of reference designate corresponding parts in the several figures:

Fig. 1 is an end view of a drop end gondola car having the end gate hinged to the body in accordance with my invention;

Fig. 2 is a partial vertical section on a larger scale, taken on line 2—2 of Fig. 1;

Fig. 3 is a partial section taken on the line 3—3 of Fig. 1; and

Fig. 4 is a plan section taken on the line 4—4 of Fig. 1.

In the drawings I have shown a conventional form of drop end gondola car to which the hinging arrangements of my invention are applied. I have shown a gondola car 10 having side walls 11, end gate 12, center sills 13, end sill 14, and flooring 15. Angular members 16 and 17 are bolted or otherwise secured to the inner and outer surfaces of the vertical edges of the side walls and form vertical abutments 18 against which the lateral edges 19 of the end gate rest. A plate 20 extending across the car and riveted or otherwise secured to the end sill and having a vertical flange 21 provides an abutment for the lower edge of the end gate. The vertical flange 21 is positioned so as to be flush with the inner surface of the angular member 16 and for this purpose the lower portions of angular members 16 and 17 are displaced outwardly at 22. The vertical and lower abutments are adapted to hold the gate in place under the pressure of the cargo. However, as will be hereinafter described, I provide other means for holding the lower edge of the gate in place. Latch members 23 of any suitable design are provided for holding the gate in its upright position. The end gate 12 is shown herein as consisting of a metal sheet 24 reinforced by corrugations 25 pressed therein, which extend horizontally across the end gate and merge into the plane thereof at their ends so as to provide flat marginal portions for contact with the abutments to prevent the leakage of the contents of the car. The margins of the sheet 24 are bent inwardly at right angles to form flanges 26, 27 and 28 along the lateral upper

edge of the sheet 24. The flanges 26, 27 and 28 are bolted to the side walls 11 and the angular members 16 and 17. The lower edge of the sheet 24 is held in place by the vertical flange 21 and the lower portions of the angular members 16 and 17. The latch members 23 are provided for holding the gate in its upright position. The end gate 12 is shown herein as consisting of a metal sheet 24 reinforced by corrugations 25 pressed therein, which extend horizontally across the end gate and merge into the plane thereof at their ends so as to provide flat marginal portions for contact with the abutments to prevent the leakage of the contents of the car. The margins of the sheet 24 are bent inwardly at right angles to form flanges 26, 27 and 28 along the lateral upper

and lower edges. These flanges further reinforce the end gate which thus forms a very strong and durable structure for supporting the weight of the cargo, whether the gate be 5 in upright position or lying upon the floor, as shown in dotted lines at 29 in Figs. 2 and 3. In order to further reinforce the flange 28 when the door is lying on the floor of the car, I secure an angle 27^a thereto, as shown, 10 so as to provide an extended surface upon which the edge of the gate may rest, and for resisting distortion of the gate under such load as may bear upon it.

The end gate is hingedly connected to the 15 body of the car so as to permit it to assume either a standing or a lying position, as previously described. The hinge construction consists of links 30 and 31, loosely connected to the lower edge of the gate by means of 20 loops 32 and 33 having elongated openings 34 therein, said links 30 and 31 extending downwardly and in opposite directions, and flexibly connected to the body or underframing 25 of the car. As herein shown, though obviously this construction depends upon the particular design of car to which my invention 30 is applied, the link 30 is connected to one of the center sills 13 by means of a staple 35 having an elongated opening 36 therein. This staple is located inwardly and below 35 the point of connection of the links to the gate. The links 31 are flexibly connected to the car by means of staples 37 having elongated openings 38 therein which are shown 40 as secured to the underside of the plate 20. The loops 32 and 33 and the staples 35 and 37 are so positioned that when the gate is closed the links 30 and 31 will be placed in tension by the thrust of the lading on the 45 end gate. The openings in the loops and staples are made sufficiently long so as to allow the links 30 and 31 to move therein when the gate is lowered to its position 29 on the floor of the car. Suitable openings 50 39 and 40 are made in the floor 15 of the car so as to permit the passage of the links 30 and 31 and receive the loops 32 and 33 when the gate is lowered.

It will be seen that the links 30 and 31 55 provide a very effective means for preventing the lower edge of the gate from rising, and consequently for checking the tendency of the end gate to bulge under the pressure of a cargo. With both the link 30 and the links 31 in tension, the lower edge of the 60 gate is held against any possibility of movement such as would permit bulging. The construction also prevents any possibility of the door rising as a whole. The side hinges resist the upward thrust of the cargo. The 65 center hinge resists both upward and outward thrust.

While I have illustrated my invention in connection with a certain type of gondola car, it is obvious that the principle of my

invention may be applied to cars of different designs without departure from the spirit of my invention. I therefore do not wish to limit myself to the specific embodiment of the invention herein shown and described, 70 except so far as specific limitations may appear in the appended claims.

I claim:

1. In a drop end gondola car, the combination with the body of the car, of a drop 75 end gate and means for flexibly connecting said gate to the car body, comprising links secured to the lower edge of the gate and to the car body which stand at an angle to each other and are put in tension by the thrust of 80 the cargo on the gate.

2. In a drop end gondola car, the combination with the underframing of the car, of a drop end gate for the car, and means for flexibly connecting said gate to said underframing, comprising a series of links extending in different directions and secured to the lower edge of the gate and to the underframing for holding the lower edge of said gate 85 in place against the outward and upward thrusts of the cargo.

3. In a drop end gondola car, the combination with the underframing of the car, of a drop end gate for the car, and means for flexibly connecting said gate to said 95 underframing, comprising a series of links extending in different directions and secured to the lower edge of the gate and to the underframing so as to hold the lower edge 100 of said gate in place against the tendency of the same to bulge and to rise above the floor of the car.

4. In a drop end gondola car, the combination with the underframing of the car, of a drop end gate for the car, and means for 105 flexibly connecting said gate to the said underframing, comprising a tension link and a link connected to the car in advance of the rear edge of the gate which co-operate to hold the lower edge of the door in position 110 against the outward and upward thrusts of the cargo.

5. In a drop end gondola car, the combination with the underframing of the car, of a drop end gate for the car, and means for 115 flexibly connecting said gate to the said underframing, comprising a tension link secured near the center of the lower edge thereof, and a link secured near the vertical edge of said gate and attached to the 120 car in advance of the rear edge of said gate, which links co-operate to hold the lower edge of said gate in position against the tendency to bulge and to rise due to the thrusts of the cargo.

6. In a drop end gondola car, the combination with the underframing of the car, of a drop end gate for the car, and means for flexibly connecting said gate to the said underframing, comprising a tension link se- 130

cured near the center of the lower edge of said gate and links secured to said lower edge on opposite sides of said tension link and attached to the car in advance of the 5 rear edge of the gate, said links co-operating to hold the lower edge of the gate in position against the tendency to bulge and to rise due to the thrusts of the cargo.

7. In a drop end gondola car, the combination with the center sill and end sill thereof of a drop end gate for the car, and means for flexibly connecting said gate to said car, comprising a tension hinge secured to the lower edge of the gate and to said center 15 sill and hinges secured to the lower edge of said gate on opposite sides of said tension hinge and attached to said end sill.

8. In a drop end gondola car, the combination with the side walls and underframing of the car, of a drop end gate for the car, abutments for said gate secured to the side walls, an abutment for the lower edge of said gate, and means for hingedly connecting said gate to the underframing comprising an inwardly extending link connected to the lower edge of said gate near its center and to said underframing and outwardly extending links on opposite sides of said first mentioned link and connected to the lower edge of said gate and to said underframing whereby the lower edge of the gate is held in place against the tendency 25 to rise and to bulge outwardly.

9. In a drop end gondola car, the combination with the center sill and end sill of the car, of a drop end gate for the car, an abutment for the lower edge of said gate, comprising an angular member extending transversely of the car, and means for hingedly connecting said gate comprising a link flexibly connected to the lower edge of said gate near its center and to said center sill and other links connected to the lower edge of said gate on opposite sides of said first mentioned link and extended outwardly and flexibly connected to said end sill.

10. In a drop end gondola car, the combination with the center sill and end sill of the car, of a drop end gate for the car, an abutment for the lower edge of said gate, and means for attaching said gate to the car comprising oppositely inclined link members flexibly connected to the lower edge of said gate and to said center and end 55 sills.

11. In a drop end gondola car, the combination with the center sill and end sill of the car, of a drop end gate for the car, an abutment for the lower edge of said gate, and means for attaching said gate to the car comprising link members flexibly connected to the lower edge of said gate and to said center sill and end sill on opposite sides of the plane of the gate.

65 12. In a drop end gondola car, the com-

bination with the center sill and end sill of the car, of a drop end gate for the car, an abutment for the lower edge of said gate, and means for attaching said gate to the car comprising a link flexibly connected to the 70 lower edge of said gate and to said center sill at a point inside the plane of the gate and other links flexibly connected to the lower edge of said door and to said end sill.

75

13. In a drop end gondola car, the combination with the underframing of the car of a drop end gate for the car and means for hingedly connecting said gate to the underframing comprising a link flexibly connected to the lower edge of said door near the middle and to said underframing at a point inside the plane of the gate and other links hingedly connected to said lower edge and to said underframing at points outside 85 the plane of the gate.

14. In a drop end gondola car, the combination with the underframing of the car of a drop end gate for the car and means for hingedly connecting said gate to the underframing comprising a link flexibly connected to the lower edge of said gate near the middle and to said underframing at a point inside the plane of the gate and other links flexibly connected to said lower edge on opposite sides of said first mentioned link and to said underframing at points outside the 90 plane of the gate.

95

15. In a drop end gondola car, the combination with the body of the car, of an end 100 gate, means on the body of the car providing abutments for the edges of the end gate when the latter is in closed position, and means connecting the gate to the body of the car comprising a hinge forming member 105 engaged with the lower edge of the gate and with the body of the car at a point inwardly of and below the lower edge of the gate, and other hinge forming members engaged with the lower edge of the gate and with the 110 body of the car at points outwardly of and below the lower edge of the gate, which members resist the tendency of the gate to rise and to bulge outwardly under the pressure of the cargo.

115

16. In a drop end gondola car, the combination with the underframing of the car, of a drop end gate for the car and means for hingedly connecting said gate to the underframe, comprising a series of elongated 120 loops connected to the lower edge of said gate, a staple having an elongated opening secured to said underframing at a point inside and below the lower edge of the gate, other staples having elongated openings 125 connected to said underframing at points outside of and below the lower edge of the gate and links connecting said staples with said loops, said staples so positioned as to put the links in tension when the gate is 130

closed and to allow play when the gate is opened.

17. In a drop end gondola car, the combination with the center and end sills of the car, of an end gate and means for hingedly connecting said gate to said car comprising an elongated loop secured to the inner lower edge of said gate, a staple having an elongated opening therein secured inwardly of and below said loop to the center sill, and a link connecting said loop and said staple, similar loops connected similarly to said gate and on opposite sides of said first mentioned loop, and other staples having elongated openings connected to said end sill below and outwardly of said similar loops and links connecting said last mentioned loops and staples.

18. A hinge construction for the end gate of a drop end gondola car, comprising a link

flexibly connected to the lower edge of the gate near its center and to the car body at a point inwardly of and below the lower edge of the gate, and other link members flexibly connected to the lower edge of the gate 25 on opposite sides of the first mentioned flexible connection and to the car body at points below and outwardly of the lower edge of the gate.

19. A hinge construction for the end gate 30 of a drop end gondola car, comprising a link loosely hinged to the gate near its center and to the car at a point inwardly of and below the hinged connection on said gate, and other links loosely hinged to said gate on opposite 35 sides of the first named hinge and to the car at points outwardly of and below their respective hinge connections on said gate.

VINTON E. SISSON.
